UNITED STATES PATENT OFFICE.

CHARLES H. ALLEN AND CHARLES A. MOORE, OF CHICAGO, ILLINOIS.

TALKING-MACHINE REPRODUCER.

Application filed August 25, 1920, Serial No. 405,827. Renewed August 22, 1923.

To all whom it may concern:

Be it known that we, CHARLES H. ALLEN and CHARLES A. MOORE, citizens of the United States, and residents of the city of Chicago, in the county of Cook and State of Illinois, have invented certain new and useful Improvements in a Talking-Machine Reproducer; and we do hereby declare that the following is a full, clear, and exact description of the same, reference being had to the accompanying drawings, and to the numerals of reference marked thereon, which form a part of this specification.

This invention relates to talking machines and more particularly to the reproducers thereof, with a view to improving the tone qualities and the adaptability of the machine. Hitherto it has been usual in talking machine construction to provide a diaphragm which covers the end of a tube leading to a horn, whereby sound waves are transferred to the horn and therein amplified. In the vibration of such a diaphragm two sets of air waves are set into motion, one on each side of the diaphragm, but it will be seen that only one set of air waves is utilized, namely, those on that side of the diaphragm which pass into the tube or amplifying horn, the duplicate set of air waves generated on the opposite side of the diaphragm being dissipated in the air and therefore lost on account of their not being amplified. It will be seen, therefore, that only a maximum of fifty per cent of all the air waves generated could be utilized in the reproduction of sound.

One of the objects of this invention, therefore, is the utilization of a maximum amount of the sound waves generated by a vibrating diaphragm by leading a sound conducting tube from each side thereof.

Hitherto most of the reproducers used in phonographs were adapted to reproduce only one particular sort of vibrations from the record or disk. As is well known, some of the records now in use employ indentations for the transmission of sound which are in a horizontal plane or are wavy lines in the surface of the disk and other records employ indentations which are made in a vertical plane in the disk and are undulatory. In other words, the production of sound in some records is accomplished by means of vibrating the point of the needle in a horizontal or transverse plane, and in other records the point of the needle is vi-

brated in a vertical plane. Now, in order to use both types of records on one machine, it has been hitherto necessary to shift the point of the needle through an angle of approximately 90 degrees in order to attain the full benefit from the vibrations which were produced in planes 90 degrees apart.

Another object of this invention, therefore, is to produce a phonograph reproducer which will reproduce sound from both records which have their vibrational impressions in horizontal and in vertical planes without any shift of the needle or of the reproducer.

A still further object of this invention is the provision of an improved form of reproducer whereby all the vibrations from the record or disk are transmitted directly to the diaphragm, but without imposing any undue strain on the diaphragm due to the weight of the reproducer or other causes.

A further important object of this invention is to provide a phonograph reproducer which can be readily taken apart and which can be removed from the remainder of the reproducer assembly with a minimum of time and effort.

Other and further important objects of this invention will be apparent from the disclosures in the specification and drawings.

The invention (in a preferred form) is illustrated in the drawings and hereinafter more fully described.

In the drawings:

Figure 1 is a side elevation, partly in section, of our improved form of phonograph reproducer shown as applied to a disk record.

Figure 2 is a rear elevation of the same, the tube to the amplifying horn being omitted.

Figure 3 is a bottom plan view of the same.

Figure 4 is a sectional view of the reproducer and of the tube leading to the amplifying horn showing the method of attaching the reproducer to the tube.

Figure 5 is a sectional view taken on the line 5—5 of Figure 4, looking in the direction indicated by the arrows.

Figure 6 is a detail view showing the method of attaching the diaphragm to the pivoted needle holder.

As shown on the drawings:

The reference numeral 10 indicates the tube of an ordinary phonograph which leads

from the reproducer to the amplifying horn. However, in this construction the tube terminates in two branches 12 and 14, which are made in the shape of a U and the ends 5 of which are adapted to fit into corresponding tubular portions 16 and 18 in the reproducer member. It is to be noted that the sum of the sectional areas of the tubes 12 and 14 is equal to the area of the horn 10 at 10 the point of junction therewith and from said point of junction the horn 10 gradually expands. This construction is a material factor in adding to the tonal qualities of the device. These tubular portions 16 and 18 15 are bent toward each other in the reproducer and terminate in chambers 20 and 22 respectively, one on each side of a diaphragm 24 located in the middle of the reproducer. This diaphragm 24 is held in place by an 20 ordinary packing 26, through which passes screws 27 for holding the reproducer and diaphragm in assembled condition.

Attached to the diaphragm 24 by means 25 of a nut 28 is a pin or light bolt 30, which extends downwardly through the chamber 22 and lower tube 18 and out through a small aperture 32 in the reproducer. The bolt 30 is screw-threaded at its end and adapted to screw into a needle-holding member 34, which is pivoted at 36 to two downwardly extending lugs 38, which are integral 30 with the bottom plate of the reproducer.

The needle holding member 34 is provided with an ordinary knurled screw 40 35 for the purpose of holding the needle 42 in position. Adjustably held in place on the bottom of the reproducer by means of a screw 44, is a leaf spring 46, which rests upon the top of the needle holding member 34 and coacts therewith to resiliently support the same and thereby act to take part 40 of the weight of the reproducing member from the diaphragm.

The operation is as follows:

45 The needle 42 is placed in contact with the record or disk and the record accordingly revolved, whereupon the needle will be vibrated and such vibration will be transmitted to the diaphragm 24 through the bar 50 or pin 30. Sound waves, upon being set up by the vibration of the diaphragm 24, will be transmitted in both directions through the tubes 16 and 18 and through the U-shaped member 12 and 14 into the main 55 tube 10, from which they are delivered to the amplifying horn. It will be seen that in this manner no sound waves are dissipated in the air, all of them which are generated by the motion of the diaphragm being re- 60 tained in the reproducer and transmitted in their full volume to the amplifying horn by means of the tubes 16, 18, 12, 14 and 10.

65 It will be seen that the needle 42 is so mounted that vibrations of its point in either a horizontal or a vertical plane will be trans-

mitted to the diaphragm 24 with equal ease regardless of the plane in which the depressions in the record are produced. Any vibrations in a vertical plane will be transmitted in vertical waves directly through the 70 needle 42, the needle holding member 34 and the bar 30 to the diaphragm 24. Likewise vibrations in a horizontal plane will be followed by the point of the needle 42, making it vibrate in a horizontal plane. 75 These vibrations will be along an arc of that circle which has its center at the pivot point 36 and will accordingly be transmitted through the bar or pin 30 to the diaphragm 24 in practically the same manner as vibrations resulting from depressions in the record which have their wave lines in a horizontal plane. 80

It will further be noted that the weight 85 of the reproducer, which would ordinarily be entirely supported by the diaphragm 24, is taken up by the spring 46, which thereby supports the reproducer through the needle holding member 34. Should the tension in the spring 46 become lessened, it can 90 easily be adjusted by means of the screw 44, thereby taking all or part of the weight of the reproducer, accordingly as desired.

It will be seen that herein is provided a phonograph reproducer which is adapted to reproduce notes from records in which the sounds were recorded by means of a recording needle, the point of which vibrated in either a horizontal or a vertical plane. Usually a record which has had its notes 100 recorded thereon by means of a recorder the point of which vibrates in a horizontal plane cannot have its sound reproduced by means of a reproducer whose point will 105 vibrate in only a vertical plane, and it therefore becomes necessary to shift the reproducing needle through an arc or angle of approximately 90 degrees in order to accommodate the needle to the vibrations which 110 were recorded in the other disk or record. It will further be seen that the entire weight 115 of the reproducer and part of the weight of the horn 10 can be supported by means of the spring 46, the whole or part of the weight of these parts being taken off the 120 diaphragm, which would otherwise support them, according to the tension in the spring which is adjusted by means of the screw 44 according to the will of the operator. It 125 will likewise be observed that all of the sound waves propagated from the diaphragm are retained within the tubes 16 and 18 and transmitted through the tubes 12, 14 and 10 into the amplifying horn, which is not the case with any of the reproducers now on the market, in which at least half of the sound waves produced are dissipated in the air and wasted on account of the fact that the sound carrying tube is located on only one side of the diaphragm, 130

whereby a maximum of only 50 per cent of the sound waves propagated by the diaphragm can be taken advantage of.

We are aware that numerous details of construction may be varied through a wide range without departing from the principles of this invention, and we therefore do not purpose limiting the patent granted otherwise than necessitated by the prior art.

10 We claim as our invention:

In a phonograph reproducer, a pivot parallel to the plane of the record and to the direction of travel thereof, an arm on said pivot, the arm being approximately parallel to the plane of the record and at right angles to the direction of travel of the record, a needle holder rigid with said arm at right angles to the plane of the

record, and a connection for said arm to the diaphragm in line with the needle holder, the distance from the record to the arm when in position to bring the needle against the record being approximately equal to the distance from said pivot to the needle holder, whereby records of the undulating type and records of the sinuous type can be played with equal effectiveness. 20 25

In testimony whereof, we have hereunto subscribed our names in the presence of two subscribing witnesses.
